UNITED STATES PATENT OFFICE.

JOSEPH M. TROWBRIDGE, OF UNITED STATES ARMY.

IMPROVEMENT IN TELESCOPIC SIGHTS FOR FIRE-ARMS.

Specification forming part of Letters Patent No. 41,874, dated March 8, 1864.

To all whom it may concern:

Be it known that I, JOSEPH M. TROWBRIDGE, of United States Army, have invented a new and useful Telescopic Sight for Fire-Arms; and I do hereby declare the following to be a full, clear, and exact description thereof, reference being had to the accompanying drawings, making part of this specification.

My invention has for its object, first, such arrangement and application of the telescope to fire-arms as shall free it from liability to derangement or dislodgment by the ordinary accidents incident to military and sporting uses; second, a provision for determining approximate distances and ranges for military purposes.

Figure 1 is a side view, representing a "Ballard" rifle mounted with my telescopic sight. Fig. 2 is an enlarged transverse section through the diaphragm. Fig. 3 is an enlarged longitudinal section of that part of the sight near the diaphragm.

A is the stout tube of wrought-iron or steel, less than one-half the length of an ordinary gun-barrel, and permanently affixed to the barrel by means of straps *a a'*, or equivalent means, and extending in rear of the gun-barrel sufficiently to come naturally to the eye when aiming. In the tube A is a diaphragm consisting of an annulus, D, bearing one vertical and several horizontal cross-wires. Springs E E', reacting against set-screws F F', hold the diaphragm D to any position, horizontal or

vertical, to which it may be adjusted by means of the said screws. Such adjustment, when once correctly made, will not require to be disturbed, as the several horizontal wires, each marking a different range, afford all the changes of elevation required in use, and the lateral adjustment remains fixed. The horizontal wires also serve to measure distances in military engagements at long range.

The above described invention is adapted and intended to be used with ordnance as well as with small-arms.

Being aware that telescopic sights have before been used consisting of cross-wires fixed in movable telescopes, the following is what I claim as new in my invention and desire to secure by Letters Patent:

1. A cross-line diaphragm mounted adjustably within a telescope attached rigidly to a fire-arm, whereby the instrument is rendered secure from derangement by ordinary military and sporting usage.

2. Securing the diaphragm D adjustably within the telescope A by springs E E', reacting against set-screws F F', substantially as and for the purposes set forth.

In testimony of which invention I hereunto set my hand.

J. M. TROWBRIDGE.
